UNITED STATES PATENT OFFICE.

CHARLES F. STALLBAUM, OF EVERETT, WASHINGTON.

DESIGN FOR A FLOOR-LAMP BODY.

Application filed May 31, 1928. Serial No. 26,926. Term of patent 3½ years.

To all whom it may concern:

Be it known that I, CHARLES F. STALLBAUM, a citizen of the United States, residing at Everett, in the county of Snohomish and State of Washington, have invented a new, original, and ornamental Design for a Floor-Lamp Body, of which the following is a specification, reference being had to the accompanying drawing, forming part thereof.

The figure is a view in elevation of my invention.

I claim:

The ornamental design for a floor lamp body as shown.

CHARLES F. STALLBAUM.
